(57) **CLAIM**

I claim the ornamental design for a personal massager, as shown and described.

DESCRIPTION

FIG. 1 is a bottom perspective view of a personal massager showing my new design.

FIG. 2 is a top perspective view showing a side view of the new design.

FIG. 3 is a front view showing the new design.

FIG. 4 is a rear view showing the new design.

FIG. 5 is a bottom view showing the new design.

FIG. 6 is a top view showing the new design.

FIG. 7 is a left-side view of the new design, which is a mirror image of the right-side view of the new design; and, FIG. 8 is a cross-sectional view of the new design, as taken along line 8-8 shown in FIG. 6.

The shading lines shown in the drawings represent the approximate three-dimensional contour of the design, and are not intended to indicate surface decoration.

The broken line(s) shown in the drawings are for the purposes of illustrating portions of the personal massager which form no part of the claimed design.
